UNITED STATES PATENT OFFICE.

THOMAS W. FITZGERALD, OF STANLEY, NEW YORK.

SAFETY KETTLE.

Application filed March 26, 1928. Serial No. 264,679.

This invention relates to an improved kettle which is characterized by the provision of a novel sectional cover and a cooperating handle structure.

5 My main object is to restrict the size of the discharge opening of the kettle and to provide a sectional hinged cover therefor with operating means for the hinged section, and a handle located beyond the cover in a position 10 to avoid burning of the fingers by escaping steam.

In the drawing:—

Figure 1 is a perspective view of a kettle or utensil constructed in accordance with the 15 present invention,

Figure 2 is a longitudinal sectional view showing the method of operation.

Referring to the drawings by reference characters it will be seen that the numeral 3 20 designates a container having a segmental solid top portion 4 terminating in spaced relation from one side to provide a discharge opening. On the last named side is a pouring spout 5. The cover comprises a small lid 6 for the spout which is hinged as at 7 to a larger lid or cover 8 for the main discharge opening. An operating link 9 is connected to the hinged lid section 6 by way of a short rigid arm 10 on the lid, the link having a 25 finger hook 11. This link is adapted to be pushed forwardly to an opening in the cover section 8 to permit the section 6 to be swung up to the dotted line position shown in Figure 2.

30 The section 8 is hinged as at 12 to the rigid top portion 4 and carries a depending arm 13 with which a push rod 14 is connected. This push rod terminates in the form of a finger hook 15.

40 Fastened to the top is a sheet of asbestos 16 upon which the handle structure 17 bears. The handle structure comprises a substantially U-shaped portion or arch 18 whose downturned ends are rigidly secured to the 45 top 4 close to the hinge 12 and an integral handgrip 19 extending at right angles from the central portion of the arch and including a downturned part 20 rigidly fastened to the top of the container.

50 From the foregoing description and drawing it will be seen that the principal feature

is in providing the container with restricted openings having a sectional cover wherein the sections are hingedly connected together so that they may be operated together or so 55 that one of the sections may be operated individually. This cover structure together with the rigid handle mounted in a position to prevent burning of the fingers by escaping steam constitutes the principal novelty of the 60 invention.

It is believed that the construction as well as the operation and advantages of the invention will be clear after reading the foregoing 65 description in connection with the accompanying drawings, and therefore a more lengthy description is thought unnecessary.

Minor changes coming within the field of invention claimed may be resorted to if desired.

Having described my invention, what I claim is:—

1. In a utensil of the class described, a hollow container provided with a rigid top terminating in spaced relation from one side 75 to provide a discharge opening, there being a spout formed on said one side and in communication with said opening, a cover comprising hingedly connected sections, one covering the main discharge opening and the 80 other covering the spout, said sections being hingedly connected together, and operating members connected with said cover sections.

2. In a utensil of the class described, a hollow container provided with a rigid top terminating in spaced relation from one side wall to provide a discharge opening, there being a spout formed on said one side and in communication with said opening, a cover comprising hingedly connected sections, one 85 covering the main discharge opening, the other covering the spout, said sections being hingedly connected together, and operating members connected with said cover sections, together with a rigid handle structure 90 mounted on the rigid top portion of the container.

3. In a utensil of the class described, a hollow container provided with a rigid top terminating in spaced relation from one side wall to provide a discharge opening, there being a spout formed on said one side and in 100

communication with said opening, a cover comprising hingedly connecting sections, one covering the main discharge opening, the other covering the spout, said sections being hingedly connected together, operating members connected with said cover sections, together with a rigid handle structure mount-

ed on the rigid top portion of the container. said handle structure embodying an arch and a right angularly disposed hand grip having a depending end portion connected to said container. 10

In testimony whereof I affix my signature.
THOMAS W. FITZGERALD.
